UNITED STATES PATENT OFFICE.

HARRY S. KUHN, OF WAYNESBORO, PENNSYLVANIA.

VICE.

1,150,041.

Specification of Letters Patent. Patented Aug. 17, 1915.

Application filed October 5, 1914. Serial No. 865,107.

To all whom it may concern:

Be it known that I, HARRY S. KUHN, a citizen of the United States, residing at Waynesboro, in the county of Franklin and State of Pennsylvania, have invented a new and useful Vise, of which the following is a specification.

The present invention relates to improvements in vises, one object of the invention, being the provision of a novel form of base construction, by means of which the vise carrying member may be adjusted and locked at any desired angle, the means for causing the manipulation of the same being simple and in ready access to the operator so that such adjustment may be obtained at will.

A further object of the present invention, is the provision of a base member, and a swingingly mounted jaw carrying member connected thereto, such member being provided with coöperative means whereby the jaw carrying member may be locked at any desired angularity with relation to the base member, the means for operating being in ready access to the operator and carried bodily by the jaw member.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

In the drawings—Figure 1 is a side elevation of the complete vise embodying the present invention. Fig. 2 is a section taken on line 2—2 of Fig. 1. Fig. 3 is a bottom plan view of the complete vise. Fig. 4 is a perspective view of the locking member. Fig. 5 is a detail view.

Referring to the drawings, the numeral 1 designates the attaching lugs of the base 2, which is made in the form of an annular member having the shouldered portions 3 and 4, the shouldered portion 3 being provided with teeth or serrations, the purpose of which will presently appear.

The jaw carrying member 5 is provided with the circular projection 6, which is rotatably mounted within the base 2 adjacent the shouldered portion 4 and is held in place thereupon by means of the screw 20 disposed

concentrically thereof. Thus the jaw carrying member 5 with the projection 6 is so mounted as to permit of the ready rotation of the jaw member 5 relatively to the stationary base so that the jaws thereof may be disposed at any desired angularity. At one side of the jaw portion of the member 5 is a vertical bore 7 for the reception of the cylindrical portion 8 of the manipulating member 9, said member 9 being provided with the slidable pin 10 so that the member 9 may be rotated and operate the screw threaded end 15 thereof, the purpose of which will presently appear. In order that the member 9 may be locked against withdrawal, the same is recessed as at 11 for the reception of the locking member 12 which is a sectional ring, as shown in Fig. 5 and is carried by the supporting portion of the jaw carrying member 5 as clearly illustrated in Fig. 2. The lower end of the member 8 is mounted for rotation through the opening 13 of the limiting disk 14, which fits below the shoulder 4 within the toothed portion 3 of the base 2 and is thus held against rotation by means of the member 8.

The member or arm 17 is provided with the threaded socket 16 for the reception of the threaded end 15 of the member 8, so that when the member 8 is rotated, the member 17 will have its free end moved to or from the toothed portion 3 of the base 2, the opening 18 thereof being loosely fitted upon the head 19 of the bolt 20 so as to permit of the necessary swinging movement, which in a device of this character is exceedingly small. It will thus be seen that by the manipulation of the stud or member 8, that the segmental head 21 of the arm or member 17 is so moved relatively to the teeth 3, as to place its teeth 22 into or out of engagement with the teeth 3 so as to form a means whereby the jaw member 5 is locked at any desired position relatively to the base 2.

The head 19 of the bolt 20 is merely a centering means and a pivotal point for the arm 17 inasmuch as the threaded end 15 of the member 8 retains the same in the desired position. The disk 14 is revoluble with the member 5 as the same is rotated to assume any desired adjustment relatively to the base 2.

From the foregoing description, it is evident that when it is desired to rotate or change the adjustment of the jaw carrying member 5 relatively to the base 2, it is

merely necessary to manipulate the stem or member 9 through the rod 10, so that the threaded portions 15 and 16 will cause the teeth 22 to be disengaged from the teeth 3, 5 at which time the member 5 may be rotated carrying with it the disk 14 and arm 17. After the same has reached the desired position, the member 9 is operated in the opposite direction by the rod 10 to cause the 10 teeth 22 to be moved into engagement with the teeth 3, thus locking the jaw member 5 fixedly with relation to the base member 2.

What is claimed is:

1. A vise, including an annular base provided with a plurality of peripheral teeth upon the under side thereof, a jaw member having a cylindrical portion fitting within the annular member for rotation, a pin for connecting the jaw carrying member to the 20 base member, an arm mounted upon said pin for rotary and lateral movements, the outer end of said arm being provided with teeth for coaction with the teeth of the base, and manually controlled means mounted in the 25 base and engaging the free end of the arm for moving the teeth thereof into and out of engagement with the teeth of the base.
2. A vise, including an annular base member provided with a plurality of radial 30 teeth therewithin, a jaw member provided with a cylindrical shouldered portion rotatably mounted in the base, a disk engaging the base and connected to the jaw carrying member for securing the jaw carrying member for securing the jaw carrying member to the base, an arm carried by the jaw carrying member and having its free end toothed and disposed for coöperation with 35

the teeth of the base, the free end thereof being disposed for movement to and from the teeth of the base, and manually controlled means mounted in the jaw carrying member and engaging the free end of the arm for moving the teeth thereof into and out of engagement with the teeth of the base.

3. A vise, including an annular base member provided with a plurality of radial teeth therewithin, a jaw member provided with a cylindrical shouldered portion rotatably mounted in the base, a disk engaging the base and connected to the jaw carrying member for securing the jaw carrying member to the base, an arm carried by the jaw carrying member and having its free end toothed and disposed for coöperation with the teeth of the base, the free end thereof being disposed for movement to and from the teeth of the base, said arm being provided with an interiorly screw threaded socket adjacent the free end thereof, and a 50 stud mounted for rotation within the base and having a threaded end for engagement with the socket, whereby with the manipulation of the stud, the arm is moved to and from the base to engage and disengage the 55 teeth thereof.

In testimony that I claim the foregoing as my own, I have hereto affixed my signature in the presence of two witnesses.

HARRY S. KUHN.
